UNITED STATES PATENT OFFICE.

LAWRENCE J. COONEY, OF PITTSBURGH, PENNSYLVANIA, ASSIGNOR TO KEYSTONE GRINDER AND MANUFACTURING COMPANY, A CORPORATION OF PENNSYLVANIA.

GRINDING MACHINE.

Application filed June 24, 1925. Serial No. 39,277.

The invention relates to grinding machines, and particularly to machines for grinding the saw tooth sickle blades used upon mowers and reapers. The machine in its preferred form contemplates the use of an ordinary hand operated grinding wheel, equipped with an attachment adapting it for the particular use above recited, and designed to be used for all classes of grinding to which the ordinary disc type abrasive wheel is applied when the attachment is removed; but the invention is not limited to this transformation feature or to the use of a hand driven wheel.

The invention has for its objects the provision of a simple construction which can be sold at a low price, and which can be used by the purchaser, who is not a skilled mechanic, to quickly and accurately sharpen saw tooth sickles which have become dulled in service. More specifically, it has for its objects the provision of improved means for adjusting, clamping and supporting the sickle bar in position for the successive grinding operations upon its teeth; the provision of an improved arrangement for giving the bar and grinding wheel the relative movement necessary for securing the engagement of the wheel with the surfaces to be ground; and the provision of means whereby the side face of the grinding wheel may be utilized for the grinding operation, thus relieving the edge or peripheral surface from this work, so that such peripheral surface may be used for general work for a longer period than would otherwise be the case. One embodiment of the invention is illustrated in the accompanying drawings wherein:

Figure 1 is a plan view of the machine. Fig. 2 is a front elevation. Fig. 3 is an enlarged detail section on the line III—III of Fig. 1. Fig. 4 is a section on the line IV—IV of Fig. 1. Fig. 5 is a plan view of the sickle holder shown in side elevation in Fig. 4. Fig. 6 is a section on the line VI—VI of Fig. 4. And Fig. 7 is a section through the sickle holder corresponding to that of Fig. 6, but showing the sickle bar clamped in position in the holder.

Referring to the drawings, 1 is the base plate of the machine adapted to rest upon the bench 2, upon which the machine is supported, being held securely in position by means of the clamps 2^a, 2^b (Fig. 2) extend-

ing beneath the bench, and provided with the usual clamping screws 3, 3. The base plate carries the gear casing 4 in which is mounted the spur gear 5 driven from the handle 6 carried by the shaft 6^a through the intermediary of suitable gearing not shown and constituting no part of the present invention.

Extending transversely of the casing 4, and journaled therein is the spindle 7, to one end of which is secured the disc grinding wheel 8 of the alundum, or other suitable abrading composition. This shaft carries the long pinion 9 meshing with the gear 5, the shaft being slidable endwise in its bearings, and the long pinion giving driving engagement as the shaft is moved in and out. This arrangement permits of the movement of the grinding wheel 8 up to and away from the work; i. e., the sickle bar 10. This movement is accomplished by means of the lever 11 pivoted at its end to the lug 12 and carrying intermediate its ends a block 13 to which the outer end of the shaft 7 is swiveled.

The block 13 is pivoted in the lever 11 (Figs. 2 and 3) upon the screws 14, 14, held 80 against unscrewing by the cotter pins 15, 15. The reduced end of the shaft 7 carries the bushing 16, with a nut 17 holding it in position, a wear ring 18 being interposed between the nut and the face of the block 13. 85

Mounted upon the base plate 1 is the bracket 19 which carries the sickle clamp or holder 20. This bracket is swiveled upon the threaded rod 21 (Figs. 1 and 4) by means of which the bracket may be clamped in any desired position of angular adjustment. The base plate is provided with a pair of upstanding lugs 22 each carrying a stop screw 23 adapted to engage the surfaces 24, 25 on the bracket. The sickle holder 20 is provided with integral lugs carrying the bolts 26, 26 (Figs. 1 and 4) supported by the vertical posts 27, 27 integral with the bracket 19 (Fig. 4). One of the posts 27 has a rearwardly projecting arm 28 provided with a thumb screw 29 adapted to engage an arm 30 projecting rearwardly from the sickle holder, thus providing for an adjustment of the sickle holder upon the bolts 26, 26. 100

The sickle holder 20 comprises the longitudinally extending main bar 30^a and the clamping bar 31 also extending longitudinally therebeneath (Figs. 4 and 6). Fig. 7 shows the sickle clamped in position between 110

the bars 30^a and 31, such sickle comprising the supporting bar 32 and the blades 33 riveted thereto. The clamping bar is supported by the three bolts 34, 34, 34 extending 5 through the bar 30 with their heads 35, 35, 35 supported upon the inclined surface 36, 36, 36 of the locking bar 37. This locking bar is operated by the lever 38, pivoted at 39, a movement of the lever to the right serving 10 to move the bar 31 upward to clamp the sickle, and a movement to the left permitting a downward movement of such bar 31. The bar 30^a is also provided with a slotted lug 40 (Fig. 4) carrying the block 41, which may 15 be clamped in position by the thumb nut 42, such block serving as a gage, after once being set, to engage the inclined faces of the sickle cutter blades and so fix the longitudinal position of the sickle upon the holder for 20 the successive grinding operations on such blades.

The operation of grinding a sickle is as follows:

The operator first positions the sickle between the bars 30^a and 31 and slides it along until the corner α (Fig. 1) of the grinding wheel comes in line with one of the V spaces y (Fig. 2) between the edges of a pair of blades. The sickle is then clamped by operating the handle 38 and the gage block 41 (Fig. 4) positioned against the inclined edge of one of the teeth, and clamped in position to serve as a guide in positioning the sickle for the grinding operations which succeed 35 the first one. At the time the V space y is brought into opposition to the corner α of the wheel, the bracket 19 carrying the sickle holder is swung around the screw rod 21 until it arrives at the proper angle, which is 40 readily determined by the operator by moving the grinding wheel in proximity to the surface of the blade which is to be ground first. The screw rod 21 is then tightened and the stop or gage bolt 23 positioned in 45 contact with the surface 24 as illustrated, so that the position of adjustment of the bracket 19, when once determined is not lost upon loosening the screw rod. The final adjustment of the sickle holder about the bolts 26 50 as an axis is accomplished by means of the thumb screw 29, the proper angle being readily determined by the operator upon bringing the grinding surface of the wheel in proximity to the surface of the blade 55 which is to be ground.

The machine is now set for the first grinding operation, which is accomplished by the operator, who turns the handle 6 with his right hand and presses the lever 11 inward 60 with his left hand, thus moving the grinding wheel inward until its side face adjacent its

periphery engages the surface to be ground, the extent of grinding being determined by the amount the handle 11 is moved inward.

One edge of one of the blades now being 65 ground, it becomes necessary to unclamp the sickle bar and re-position it for grinding the edge of the next blade. This is done by moving the lever 38 to the left, permitting the bar 31 to move down, after which the 70 sickle is moved along the length of one of the plates 33, the exact position being fixed by having the edge of the next plate engage the gage block 41. The sickle is then clamped in position and the operation of grinding repeated. After the edges of the plates having 75 the same inclination are ground, the bracket 19 is shifted about the pivot 21, so that the screw 23 engages the surface 25, and the surfaces on the sickle to be ground approach the 80 other side of the wheel at α . The other edges of the blades are then all ground following the procedure heretofore outlined for the first set of edges.

When it is desired to use the machine for work other than the grinding of saw tooth sickles, the bracket 19 (with the parts carried thereby) and the handle 11 are readily removed, and a collar secured to the outer end of the shaft 7 by means of a set screw to prevent inward movement of such shaft. The machine may also be used for many purposes without removing the sickle attachment devices, so that it is serviceable 85 for general use.

What I claim is:

In combination, a frame including a horizontal plate adapted to rest upon a table or bench, and a gear casing at right angles to said plate, a work spindle extending transversely through the casing and mounted for rotative and longitudinal movement, lateral extensions at the sides of the casing acting as bearings for the spindle, a disc grinding wheel carried by the spindle on one side of the casing, a drive gear in the casing arranged so as to mesh with the pinion throughout the longitudinal movement of the spindle, a shaft carrying said gear and provided with a turning crank and handle on the side of the casing remote from the grinding wheel, and a hand lever pivoted at one end to the casing above said crank and having a rocking and swivel connection intermediate its ends with the end of said spindle, said crank having its end carrying the handle bent outward so as to clear said lever during its movement of rotation.

In testimony whereof, I have hereunto 120 subscribed my name this 23rd day of June, 1925.

L. J. COONEY.
